UNITED STATES PATENT OFFICE.

HOWETH TOWNSEND FORD, OF CENTRAL VALLEY, NEW YORK.

WASHING DEVICE FOR AUTOMOBILES AND OTHER VEHICLES.

1,142,689.

Specification of Letters Patent.

Patented June 8, 1915.

Application filed July 8, 1914. Serial No. 849,710.

To all whom it may concern:

Be it known that I, HOWETH T. FORD, a citizen of the United States, and a resident of Central Valley, in the county of Orange 5 and State of New York, have invented a new and Improved Washing Device for Automobiles and other Vehicles, of which the following is a full, clear, and exact description.

10 This invention relates to a sponge holder which is especially adapted to be used in connection with the nozzle of a hose, whereby the sponge can be held directly in front of the nozzle so that the sponge will be kept 15 constantly supplied with water during the washing operation, as in cleaning vehicle wheels, bodies and the like.

The invention has for its general objects to improve and simplify the construction of 20 washing devices as set forth in Letters Patent of the United States, Number 1,096,704, granted to me on the 12th day of May, 1914, whereby the sponge can be held more firmly in the holder, the holder more easily fastened with respect to the hose nozzle in a 25 position to hold the sponge in alinement with the nozzle, and whereby the device can be more conveniently handled.

With such objects in view, and others 30 which will appear as the description proceeds, the invention comprises various novel features of construction and arrangement of parts which will be set forth with particularity in the following description and 35 claims appended hereto.

In the accompanying drawing, which 40 illustrates one embodiment of the invention, and wherein similar characters of reference indicate corresponding parts in all the views, Figure 1 is a plan view of the sponge holder applied to a nozzle; Fig. 2 is a vertical section of the sponge holder with the nozzle in elevation; and Figs. 3 and 4 are 45 sectional views on the lines 3-3, and 4-4, respectively, of Fig. 2.

Referring to the drawing, A designates an ordinary hose nozzle, and B is the washing device applied to the nozzle in the form of an attachment which can be readily fastened thereon or taken off. The attachment 50 comprises a clip 1 which embraces the nozzle and is secured in position by a clamping nut 2 fastened to lugs 3 of the clip, and on this clip is a tangentially disposed bar-like portion 4 which has a longitudinal bore 5 for

receiving a pivot bolt 6 which fastens the sponge-carrying frame B to the clip. This frame comprises diverging bars or members 7 which have eyes 8 through which the pivot bolt 6 extends, such eyes being spaced apart to engage the opposite ends of the bar-like member 4 of the clip. The members 7 are connected together by a cross-bar 9 which carries a spring clip 10 of substantially U-shape form. This clip surrounds the nozzle 65 A at a point between the discharge orifice thereof and where the clamping clip 1 embraces the nozzle, and the spring clip is automatically engaged or disengaged by moving the sponge-carrying frame toward 70 or from the nozzle in a swinging movement about the bolt or pintle 6 as a center. A ring 11 is carried by the members 7, and in this ring is inserted the sponge C. The sponge is fastened in the ring by screw-bolts 12 that extend diametrically of the ring at different angles and through the sponge. These bolts effectively anchor the sponge in the holder and prevent the sponge from tearing out in the use of the device. 75 The parts 7, 8, 9 and 11 are preferably a single-piece casting, and the clip 10, which is resilient, is fastened thereto by a rivet or equivalent means 13. The clamping clip 1, which is also a metal casting, has formed 80 therewith a hollow boss 14 that extends from the part 4, and in this boss is fastened a handle 15 of any desired length, whereby the operator can conveniently use the device.

When the device is in use, the sponge 90 holder is in the full line position, Fig. 2, so that the sponge is directly in line with the nozzle 2, and the stream from the nozzle will keep the sponge wet during the washing operation. In use, the operator 95 holds the device by the handle 15. When a stream of water is to be played on the parts to be washed the sponge holder is thrown upwardly and backwardly to the broken line position, Fig. 2, where it rests against the 100 handle.

From the foregoing description taken in connection with the accompanying drawings, the advantages of the construction and method of operation will be readily understood by those skilled in the art to which the invention appertains, and while I have described the device which I now consider to be the best embodiment thereof, I desire to have it understood that the device shown 105 110

is merely illustrative and that such changes may be made when desired as are within the scope of the appended claims.

Having thus described my invention, I claim as new and desire to secure by Letters Patent:

1. A washing device of the class described comprising a sponge-holding ring, a pair of members rigidly connected with the ring, a cross-bar connected with the members, a spring nozzle-engaging clip carried by the cross-bar, and means connected with the members for attaching the device to a hose nozzle.
- 15 2. A washing device of the class described comprising a sponge-holding ring, a pair of members rigidly connected with the ring, a

cross-bar connected with the members, a spring nozzle-engaging clip carried by the cross-bar, a nozzle-embracing clamping clip 20 having a bar-like member disposed between the first-mentioned members, means for pivotally connecting the first-mentioned members with the said member of the clamping clip, and a handle connected with the clamp- 25 ing clip.

In testimony whereof I have signed my name to this specification in the presence of two subscribing witnesses.

HOWETH TOWNSEND FORD.
